(57) **CLAIM**

The ornamental design for an open stud bracket as shown and described.

DESCRIPTION

FIG. 1 is a top front left perspective view of an open stud bracket showing my new design;

FIG. 2 is a top front left perspective view thereof;

FIG. 3 is a bottom rear left perspective view thereof;

FIG. 4 is a top view thereof;

FIG. 5 is a front view thereof, the rear view being a mirror image of the front view;

FIG. 6 is a bottom view thereof;

FIG. 7 is a left side view thereof;

FIG. 8 is a right side view thereof;

FIG. 9 is a top front right environmental view thereof; and,

FIG. 10 is a bottom rear left environmental view thereof.

The dash-dash broken lines depict portions of the open stud bracket that form no part of the claimed design. The dot-dash broken lines depict environmental structure and form no part of the claimed design. The open stud bracket is shown with a symbolic break in its length. The appearance of any portion of the article between the break lines forms no part of the claimed design.
